United States Patent Office

Des. 187,776

Patented Apr. 26, 1960

187,776

GATE VALVE

Arthur Y. C. Tang, Brockton, Mass., assignor to Walworth Company, New York, N.Y., a corporation of Massachusetts

Application February 2, 1959, Serial No. 54,428

Term of patent 14 years

(Cl. D91—3)

FIG. 1

FIG. 2

FIG. 3

Fig. 1 is a front elevation of a gate valve embodying my new design;

Fig. 2 is a side elevation thereof; and

Fig. 3 is a top plan view thereof.

I claim:

The ornamental design for a gate valve, substantially as shown.
